(57) **CLAIM**

The ornamental design for a container for cell observation as shown and described.

DESCRIPTION

FIG. 1 is a front and right perspective view of a container for cell observation.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an enlarged cross sectional view taken along the line 8-8 in FIG. 2.

FIG. 9 is an enlarged cross section taken along the line 9-9 in FIG. 2 with portions beyond line 9-9 not shown; and, FIG. 10 is a magnified view of the portion 10 circled in FIG. 9.

The dashed lines shown in the drawings depict portions of the container for cell observation that form no part of the claimed design.

The dash-dot lines depict the boundary of the claimed design that form no part thereof.

1 Claim, 10 Drawing Sheets
